UNITED STATES PATENT OFFICE.

JOHN CALLAHAN, OF MILWAUKEE, WISCONSIN.

BILLIARD-CUE CLAMP.

SPECIFICATION forming part of Letters Patent No. 337,659, dated March 9, 1886.

Application filed November 17, 1885. Serial No. 183,025. (No model.)

To all whom it may concern:

Be it known that I, JOHN CALLAHAN, of Milwaukee, in the county of Milwaukee, and in the State of Wisconsin, have invented certain new and useful Improvements in Billiard-Cue Clamps; and I do hereby declare that the following is a full, clear, and exact description thereof.

My invention relates to the repairing of billiard-cues; and it consists in a device for holding the tip firmly to the end of the cue while the glue which cements them is drying, as will be more fully set forth hereinafter.

In the drawings, Figure 1 is a perspective view of my tip-clamp in use, and Figs. 2 and 3 are sectional views thereof.

A is an ordinary billiard-cue, and B the tip thereof.

C is the hollow shank or sleeve of my clamp, through which the cue is passed, and D is the loop, preferably a strip of elastic steel, though it may be of leather or other material, secured to the outside of said shank.

E is the set-screw, and F the protecting-strip, of leather or other flexible material.

When a tip is to be fastened to the end of a cue, it is first stuck on with glue, and then the end of the cue bearing the tip is pushed through the hollow shank C till it touches the top of the loop D, as shown in Fig. 2, and then the said socket is pulled downward as far as the elasticity of the loop will permit, and secured to the cue at this point by means of the set-screw E; and to prevent the end of the set-screw from entering the wood of the cue or defacing or injuring it in any way the protecting-strip F, of leather or any other suitable material, is interposed, and is crowded against the cue by the screw, effectually guarding it against the possibility of damage from

the said set-screw. When the glue is dry, and the tip thereby firmly secured to place, the screw E can be loosened and the clamp readily removed.

I am aware that a billiard-cue clamp has been employed consisting of a frame composed of centrally-perforated end plates united by converging rods or braces, the upper end plate having a spring-cap fitted thereto and sliding rubber-faced wedges adapted to be secured to said rods or braces, for the purpose of retaining the cue in place. I therefore lay no claim to such construction; but,

Having thus described my invention, what I claim as new, and desire to secure by Letters Patent, is—

1. In a device for holding a tip against the top of a billiard-cue in the operation of gluing, the combination of a hollow shank for receiving the cue, a flexible strap forming a loop to limit its movement therein, and means for securing the holder to the cue, substantially as set forth.

2. In a device for holding a tip against the top of a billiard-cue in the operation of gluing, the combination of a hollow shank for the admission of the cue, a flexible strap forming a loop to limit its movement therein, a set-screw for securing the holder to the cue, and a strip of flexible material interposed between the screw and cue, to prevent injury to the latter, substantially as set forth.

In testimony that I claim the foregoing I have hereunto set my hand, at Milwaukee, in the county of Milwaukee and State of Wisconsin, in the presence of two witnesses.

JOHN CALLAHAN.
